UNITED STATES PATENT OFFICE.

HARRY T. BUMGARDNER, OF WACO, TEXAS.

MOLD FOR CONCRETE WALL BLOCKS.

Application filed January 4, 1926. Serial No. 79,166.

To all whom it may concern:

Be it known that I, HARRY T. BUMGARDNER, a citizen of the United States, residing at Waco, in the county of McLennan and State of Texas, have invented certain new and useful Improvements in a Mold for Concrete Wall Blocks, of which the following is a specification.

This invention relates to concrete wall blocks, but has more particular reference to a mold construction for forming the same, the primary object of the invention residing in the provision of a relatively simple, but efficient form of mold wherein a plurality of blocks may be simultaneously formed, and this without requiring any great skill upon the part of the workmen.

A further and important object is to provide a mold construction wherein a plurality of wall blocks of the tongue and groove type may be formed through use of but a single mold construction.

A further and important object is to provide a mold construction wherein the shape of the interlocking tongues and grooves may be varied through reason of the provision of interchangeable molding plates.

A still further and important object is to provide a mold construction wherein a facing may be formed upon the block during the formation of the same within the mold.

Other objects will become apparent as the invention will be better understood, the same comprising the novel construction, combination and arrangement of parts hereinafter more fully described, shown in the accompanying drawing, and claimed.

In the drawings wherein like reference characters indicate corresponding parts throughout the several views:

Figure 1 is a fragmentary top plan of a mold constructed in accordance with the present invention, the top block forming plate being partly broken away for obvious reasons, the mold being disclosed as in actual use.

Figure 2 is a detail transverse section taken substantially upon the line 2—2 of Figure 1, disclosing the mold in use prior to the block facing pouring operation.

Figure 3 is a perspective of the formed block,

Figure 4 is a section similar to Figure 2, in this instance however, there has been poured into the mold a batch of facing material, it being of course necessary that the mold be constructed with a removable face plate in order that after the blocks have become somewhat hardened, the same may be removed for allowing a space for the facing material.

Figure 5 is a fragmentary perspective of the top facing plate of the mold.

Figure 6 is a similar view of a slightly modified form of top face plate, and

Figure 7 is an enlarged fragmentary perspective of a block showing the type of channel or groove formed in certain faces of a block resultant from the use of the type of plate shown in Figure 6, it being understood of course that the bottoms and end facing plates be constructed complementary to the top face plate.

Now having particular reference to the drawing, 5 indicates the mold box of suitable material, preferably wood, that is generally square in cross section, and open at its top side. Said mold box is of relatively great length, and in the construction of blocks in the type shown in Figure 3, is adapted to have removably disposed upon its bottom wall, a block bottom face plate 6 of sheet metal. Said bottom face plate 6 is formed adjacent its opposite longitudinal edges with pendent V-shaped channels 7—7, the bottom walls of which rest upon the bottom of the box 5, as clearly shown in Figures 2 and 4. For preventing sagging of the central portion of this face plate and the longitudinal edges thereof filler strips 8 and 9—9 respectively are provided.

The mold construction further constitutes the provision of a plurality of rectangular shaped block vertical air shape forming boxings 10 that are adapted to be vertically disposed in predetermined spaced relation within the center of the mold box 5 as clearly shown in Figures 1, 2 and 4.

The inner surfaces of the box side walls are provided at predetermined spaced points with registering vertical slots 11—11 within which slidably engage the opposite vertical edges of block end forming plates 12. These plates are also formed adjacent their

opposite vertical edges with vertically extending V-shaped channels 13—13 for providing the formed blocks with interlocking tongues and grooves at their adjacent ends.

5 The mold construction further constitutes the provision of a plurality of block facing strips 14, Figure 2, that are disposed within the mold block intermediate the end strips 12 and in face to face contact with the interior surface of the box front wall.

The facing strips 6, 12, and 14 are all of a smooth surfaced metal, as is also the air space forming boxings 10 in order that the resultant blocks will be provided with smooth faces. After these strips and boxings have been so disposed within the mold box 5, the material is formed and allowed to harden for producing blocks 15 of the construction more clearly shown in Figures 1 20 and 3. As shown in these figures, the blocks 15 will be of substantially rectangular shape, and will be provided with a single vertical air channel 16, the upper and one side edge thereof being formed with relatively V-shaped grooves 17 and 18 respectively, at opposite sides of the air space whereas the lower side and opposite end of the block will be provided with V-shaped tongues 19 and 20, respectively, it being obvious that 25 when the blocks are laid, the tongues and grooves of adjacent blocks will interfit for providing an interlocking means between adjacent blocks.

It is of course to be understood that after 30 the semi-fluid mass has been poured into the mold box 5, the top facing strip 21 is forced downwardly by pressure upon the top of the mold the same being provided adjacent its opposite end with pendent V-shaped channels 22—22, Figures 1 and 2.

The forward longitudinal edge of the top strip 21 is reduced in width with respect to the other longitudinal edge of the strip in order that the front facing strips 14—14 45 may be removed after the blocks have partially hardened.

After said blocks have partially hardened, these strips are removed and relatively thinner strips 14' are inserted in lieu thereof, 50 after which a facing material 23, Figure 4, may be poured between the blocks and said strips 14' for providing a smooth and artistic facing for the block.

In Figure 6 there is shown a slightly 55 modified form of top, bottom, and end facing strip 24, that is similar to the strips 6, 12, and 21 respectively, shown in Figures 1 2, 4, and 5 with the exception that the tongue and groove forming channels 25—25 of 60 relatively W-shape for forming a dual tongue and groove connection between the top, bottom, and ends of the block, one of which is fragmentarily shown in Figure 7, and designated 26.

65 It will thus be seen that I have provided

a highly novel, simple and inexpensive mold construction whereby a plurality of novel wall blocks may be rapidly formed without the requirement of a separate mold construction for each block, and of such a nature as to permit of the ready disassembly of parts for cleaning or renewal purposes, and in order that various designed top, bottom, and end facing strips may be employed.

70 Minor changes may be made in the invention without departing from the spirit and scope of the appended claims.

Having thus described the invention, what I claim as new and desire to secure by Letters Patent is:

1. In a block forming mold of the character described, a relatively elongated mold box being open at its top side, a block bottom facing strip adapted to be disposed within the box and for rest upon the bottom wall thereof, said strip being formed adjacent its opposite longitudinal edges with pendent channels, filler blocks disposed within the box beneath the bottom facing strips at the opposite sides of the pendent channels, predetermined spaced block end forming strips removably and vertically disposed within the mold box, said end forming strips being provided adjacent their opposite edges with vertical channels, and a block top facing forming strip adapted to be disposed upon the mold box after the material has been poured therein, said last mentioned strip being also provided adjacent its opposite longitudinal edges with pendent channels, the channels of all of said forming strips adapted to provide interlocking tongues and grooves upon the bottom and top, and opposite ends respectively of the block.

100 2. In a block forming mold of the character described, a relatively elongated mold box being open at its top side, a block bottom facing strip adapted to be disposed within the box and for rest upon the bottom wall thereof, said strip being formed adjacent its opposite longitudinal edges with pendent channels, filler blocks disposed within the box beneath the bottom facing strips at the opposite sides of the pendent channels, predetermined spacing block end forming strips removably and vertically disposed within the mold box, said end forming strips being provided adjacent their opposite edges with vertical channels, and a block top facing forming strip adapted to be disposed upon the mold box after the material has been poured therein, said last mentioned strip being also provided adjacent its opposite longitudinal edges with pendent channels, the channels of all of said forming strips adapted to provide interlocking tongues and grooves upon the bottom and top, and opposite ends respectively of the block.

block, and interchangeable block front face forming strips of varying thickness for removable positioning within the box intermediate the end facing strip and upon the inner side of the box front wall whereby, after the blocks being formed within the mold have partially hardened, the thick

strips may be removed and the thin strips inserted in lieu thereof for providing a facing material receiving space between the 10 block and said facing strip.

In testimony whereof I affix my signature.

HARRY T. BUMGARDNER.
